UNITED STATES PATENT OFFICE.

DAVID HILL, OF WASHINGTON, NORTH CAROLINA.

DESIGN FOR A NUT-WRENCH.

SPECIFICATION forming part of Design No. 30,115, dated January 31, 1899.

Application filed January 6, 1899. Serial No. 701,402. Term of patent 7 years.

To all whom it may concern:

Be it known that I, DAVID HILL, a citizen of the United States, residing at Washington, in the county of Beaufort and State of North Carolina, have invented and produced a new and original Design for a Nut-Wrench; and I do hereby declare the following to be a full, clear, and exact description of the same, reference being had to the accompanying drawing, forming a part thereof.

The figure represents a perspective view of my design.

As shown in the drawing, the leading feature of my design consists in the two straight bars A A, lying side by side and being disposed at a slight angle to each other, forming an opening or slot A' between them, which tapers from one end of the wrench toward the

other, and a cross-bar B, extending from one of the straight bars A A to the other a short distance from each end, the ends of the bars A A projecting beyond the cross-bars B B.

Another feature of my design is a central cross-bar C, extending from one of the bars A A to the other about midway between the cross-bars B B.

What I claim, and desire to secure by Letters Patent, is—

The design for a nut-wrench herein shown and described.

In testimony whereof I affix my signature in presence of two witnesses.

DAVID HILL.
